UNITED STATES PATENT OFFICE.

RICHARD W. OSWALD, OF BLOOMSBURG, PENNSYLVANIA.

CAR-TRUCK.

SPECIFICATION forming part of Letters Patent No. 596,449, dated December 28, 1897.

Application filed March 3, 1897. Renewed December 6, 1897. Serial No. 660,985. (No model.)

To all whom it may concern:

Be it known that I, RICHARD W. OSWALD, a citizen of the United States, residing at Bloomsburg, in the county of Columbia and 5 State of Pennsylvania, have invented certain new and useful Improvements in Car-Trucks; and I do hereby declare the following to be a full, clear, and exact description of the invention, such as will enable others skilled in the art to which it appertains to make and use 10 the same.

My invention relates to car-trucks; and it consists in the combination, with a bolster, of side frames comprising upper and lower T- 15 irons forming arch-bars for supporting said bolster and pedestals in said side frames.

It also consists in the combination, with a bolster, of side frames comprising T-shaped bars for supporting said bolster, the said T- 20 bars being formed into pedestals at their ends for receiving the journal-boxes of the truck.

It further consists in certain other novel constructions, combinations, and arrangements of parts, all of which will be hereinafter fully described and claimed. 25

In the accompanying drawings, Figure 1 is a plan view of one side of my improved car-truck. Fig. 2 is a side elevation of the same. Fig. 3 is a transverse vertical section of the 30 same, portions of the truck being shown in elevation. Fig. 4 represents a detail elevation of an improved form of pedestal used in my improved car-truck. Fig. 5 is a detail end view of the same. Fig. 6 is a detail cross-section of the T-shaped bars, no brace or spreader being interposed between them. Fig. 7 is a similar view showing the T-shaped upper bar and a channel-iron for the lower bar. Figs. 35

8 and 9 are similar views showing bars of different shape in cross-section which I contemplate using in connection with my car-truck, no spreader being shown between the bars in these constructions. 40

A in the drawings represents a car-truck constructed in accordance with my invention. 45

B is a bolster, C the side frames, and D D pedestals.

Each side frame C of the car-truck is preferably constructed by forming an arch c of a 50 T-shaped bar and an inverted arch c' also of a T-shaped bar. The T-shaped bars have

broad horizontal flanges c⁹ and vertical ribs or webs, as c⁸. These arch-bars c c' converge toward points near the pedestals, at which points they nearly meet. The upper bar c 55 then passes in an upward direction over the journal-boxes F F and pedestal-springs f f and thence downwardly in a vertical line to form one side of the pedestals. The other side of each pedestal is formed by bending 60 downwardly the ends of the lower arch-bar c'. The ends of these bars c c' are preferably connected at a point beneath the journal-boxes F F by bolts c², passing through their ends and through spacing-sleeves c³. The braces 65 or spreaders c⁴ c⁴, consisting of metallic pieces of angular shape to fit in the angles formed between the bars c c' and the pieces c⁵ c⁵, are preferably interposed between the arch-bars at the points where they come close together. 70 In order to strengthen the pedestals, U-shaped pieces c⁵ c⁵ of metal are bolted to the inner surface of the angle-bars forming said pedestals. These pieces c⁵ c⁵ and the angle-bars c c' and the braces or spreaders c⁴ c⁴ are 75 all firmly secured together by riveting or other securing means. The journal-boxes F F are of any ordinary type and are adapted to receive springs f f upon their upper sides for supporting the side frames upon the journals, 80 and cap-pieces c⁶ c⁶, having upwardly-extending flanges c⁷ c⁷, are interposed between the springs and the upper part of the pedestals, forming a broad bearing for the said side frames. 85

The bolster or transom B is preferably formed of channel-bars or I-beams b b, which are secured to the side frames at their central points. The I-beams b b are preferably allowed to extend beyond the side frames, and 90 gusset-plates b' b' are interposed between the upper surface of the I-beams b b and the lower surface of the arch-bars c c'. These gusset-plates are securely bolted or riveted to the flanges or I-beams and the flanges of 95 the T-irons forming the arch-bar c, and by extending them to the braces c⁴ c⁴ they strengthen the arch. I find that the extending of the I-beams beyond the side frames and the securing of the gusset-plates thereto forms a 100 very strong construction and assists materially in keeping the truck perfectly square.

To the central portions of the I-beams b b is secured the usual center plate b^2 for receiving the weight of the car-body. The I-beams b b are preferably braced and connected together by interposing cross I-beams b^3 and bolting or riveting them firmly to the webs of the said I-beams b b . These braces b^3 b^3 are preferably located beneath the center plate in the middle of the truck and in line with the side frames at either end of the bolster or transom B.

While I prefer to use T-shaped bars for my side frames, as illustrated in cross-section in Fig. 6, I do not wish to limit myself to this construction, for I contemplate using T-shaped bars in connection with channel-bars, as shown in Fig. 7; also, I may use double-T-shaped bars, as further illustrated in Figs. 8 and 9, without departing from the spirit of my invention.

Figs. 6, 7, 8, and 9 of the drawings, just referred to, show cross-sections of modified forms of bars in which the spreader c^4 is omitted, the sections being taken where the upper and lower bars would touch each other adjacent to a pedestal.

In Figs 4 and 5 of the drawings I have illustrated the manner of using divided pedestals in connection with my improved car-truck.

In these views the upper and lower arch-bars g g' meet above the pedestals and are secured together in a suitable manner at that point. The pedestal G is formed of divisible parts g^2 g^3 , each having sleeves g^4 at their upper ends, whereby they are adapted to be slipped onto the ends of the two arch-bars. The inner member g^2 of the pedestal is preferably permanently secured by rivets or otherwise in position upon said arch-bars, while the outer member g^3 is removably secured by removable bolts or otherwise to the outer ends of the said arch-bars. A suitable space is left between the members of the pedestal G to receive the journal-boxes and pedestal-springs. The lower ends of the members g^2 g^3 of the pedestal G are preferably connected together and braced by a tie-rod g^5 .

From the above description it will be apparent that by my simple arrangement of T-shaped bars I am enabled to construct car-trucks of very great strength. The arch-bars by means of their vertical legs c^8 possess great strength to take the vertical strain, and the pedestals are thoroughly fortified against the back or forward thrust of the wheels and journals, while on the other hand the broad horizontal flanges c^9 are competent to receive all lateral thrusts and strain.

Car-trucks constructed in accordance with my invention are not only possessed of great strength, but are extremely simple as well as cheap in construction, and can be readily made with the usual appliances and stock found in railroad-car shops.

Having now described my invention, what I claim as new, and desire to secure by Letters Patent, is—

1. In a car-truck the combination with a bolster, of side frames comprising bars having a horizontal member and one or more vertical ribs or webs forming arch-bars for supporting said bolster and pedestals formed between the ends of the said bars, substantially as described. 70

2. In a car-truck the combination with a bolster, of side frames formed of bars having a horizontal member and one or more vertical ribs or webs for supporting said bolster, pedestals formed by the ends of said side frames and braces secured between said bars, 80 substantially as described. 75

3. In a car-truck the combination with upper and lower bars having a horizontal member and one or more vertical webs, forming arch-bars secured together near their ends, a 85 bolster resting upon the upper side of the lower arch-bars and secured to the under side of the upper arch-bar and pedestals formed in the ends of said arch-bars for embracing the journal-boxes of the car-trucks, substantially as described. 90

4. In a car-truck the combination of side frames comprising bars having a horizontal member and one or more vertical webs, forming arch-bars secured together near their 95 ends, their ends being bent downwardly to form pedestals for engaging the journal-boxes of the car-truck, substantially as described.

5. In a car-truck the combination of side frames comprising top and bottom irons having a horizontal member and one or more vertical webs forming arch-bars, a bolster consisting of parallel I-beams, braces consisting of horizontal I-beams interposed between said parallel I-beams and gusset-plates interposed 105 between the bolster and the said side frames, substantially as described. 100

6. In a car-truck the combination of upper and lower irons having a horizontal member and one or more vertical webs forming arch-bars, braces interposed between their end portions, a bolster secured between the said arch-bars, and gusset-plates interposed between the arch-bars and the bolster for bracing the same and keeping the truck in true and pedestals formed in the side frames, substantially as described. 110 115

7. In a car-truck, the combination of side arch-bars forming side frames, pedestals formed between the ends of the said side arch-bars, a bolster secured between the said arch-bars at each end, the ends of the said bolster extending beyond the side bars, and gusset-plates interposed between said extended portions of the bolster and the said arch-bars for 120 125 bracing the truck, substantially as described.

8. In a car-truck the combination with a bolster, of bars having a horizontal member and one or more vertical webs forming arches for supporting said bolster, the ends of said bars being bent so as to form downwardly-extending pedestals to receive the journal-boxes, journal-boxes adapted to work in said pedestals, springs mounted upon said jour- 130

nal-boxes and spring-caps having guiding flanges interposed between said springs and the side frames, substantially as described.

9. In a car-truck, the combination with a bolster, of side frames, each formed of a bar having a horizontal member and one or more vertical webs and a channel-bar, riveted together near their ends, and pedestals formed between the ends of the said bar and the said

channel-iron for engaging the journal-boxes, substantially as described.

In testimony whereof I affix my signature in presence of two witnesses.

RICHARD W. OSWALD.
